UNITED STATES PATENT OFFICE.

WALTER A. SCHIFFER, OF NEW YORK, N. Y.

DESIGN FOR AN ADVERTISING-CARD OR SIMILAR ARTICLE.

SPECIFICATION forming part of Design No. 35,677, dated February 4, 1902.

Application filed December 4, 1901. Serial No. 84,712. Term of patent 14 years.

To all whom it may concern:

Be it known that I, WALTER A. SCHIFFER, a citizen of the United States, and a resident of the city and county of New York, borough of Manhattan, and State of New York, have invented and produced a new and original Design for an Advertising-Card or Similar Article, of which the following is a specification.

In the drawings forming part of this specification, Figure 1 is a face view, and Fig. 2 an edge view.

The essential features of my design reside in the pictorial illustration 1 of an owl superposed over a three-legged base 2, upon which is represented a cigar 3, extending diagonally

across the face of the base and from the same at one side, and upon which the owl appears to rest. Above the owl and partly embracing the head thereof is a disk 4.

I claim—

The design for an advertising-card or similar article, substantially as herein shown and described.

Signed at the city, county, and State of New York this 30th day of November, 1901.

WALTER A. SCHIFFER.
